US0D1049006S

(12) **United States Design Patent** (10) **Patent No.:** **US D1,049,006 S**
(45) **Date of Patent:** **** Oct. 29, 2024**

(54) **CAR CUP HOLDER**

(71) Applicant: **Shenzhen Yinglaifa Technology Co., Ltd.**, Shenzhen (CN)

(72) Inventor: **Yuwang Zou**, Shenzhen (CN)

(73) Assignee: **SHENZHEN YINGLAIFA TECHNOLOGY CO., LTD.**, Shenzhen (CN)

(**) Term: **15 Years**

(21) Appl. No.: **29/872,636**

(22) Filed: **Mar. 16, 2023**

(51) **LOC (14) Cl.** **12-16**

(52) **U.S. Cl.**

USPC **D12/419**

(57) **CLAIM**

The ornamental design for a car cup holder as shown and described.

DESCRIPTION

FIG. 1 is a perspective view of a car cup holder showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

1 Claim, 8 Drawing Sheets
